DESIGN FOR A TOOTHED CULTIVATOR RING

Theodore G. Schmeiser, Fresno, Calif.

Application September 20, 1941, Serial No. 103,432

Term of patent 14 years

To all whom it may concern:

Be it known that I, Theodore G. Schmeiser, a citizen of the United States, residing at Fresno, in the county of Fresno, State of California, have invented a new, original, and ornamental Design for a Toothed Cultivator Ring, of which the following is a specification, reference being had to the accompanying drawing, forming a part thereof.

In the drawing:

Fig. 1 is a fragmentary side elevational view, a portion being illustrated in dotted lines of a

toothed cultivator ring showing my new design;

Fig. 2 is an enlarged cross sectional view on line 2—2 of Fig. 1;

Fig. 3 is a similar view on line 3—3 of Fig. 1, and

Fig. 4 is an enlarged cross sectional view on line 4—4 of Fig. 2.

I claim:

The ornamental design for a toothed cultivator ring, as shown.

THEODORE G. SCHMEISER.
